Reedolff Wildermaen
ATTORNEY.

UNITED STATES PATENT OFFICE.

HENRY D. KADEL, OF BROOKLYN, NEW YORK.

DESIGN FOR AN ELECTRIC BULB.

Application filed November 8, 1927. Serial No. 24,037. Term of patent 3½ years.

To all whom it may concern:

Be it known that I, HENRY D. KADEL, a citizen of the United States, and resident of Brooklyn, New York, in the county of Kings and State of New York, have invented a new, original, and ornamental Design for Electric Bulbs, of which the following is a specification, reference being had to the accompanying drawing, forming part thereof.

Figure 1 is an elevation. Figure 2 shows

the contour of a sectional top view of an electric bulb, showing my new design.

I claim:

The ornamental design for an electric bulb, as shown.

Signed at New York in the county and State of New York this seventh day of November, A. D. 1927.

HENRY D. KADEL.
